UNITED STATES PATENT OFFICE

MERTON W. ZEMAN, OF LAKEWOOD, OHIO, ASSIGNOR TO THE OSBORN MANUFACTURING COMPANY, OF CLEVELAND, OHIO, A CORPORATION OF OHIO

CONTINUOUS CORE MAKING MACHINE

Application filed July 30, 1931. Serial No. 554,063.

The present improvements relating, as indicated, to mold and core making mechanism, have more particular regard to means for blowing sand into a core box, mold, or the like. In machines of this type a chamber containing sand is brought over the core box and air under pressure then applied to the sand in such chamber to force the same into the box. There is, however, a tendency for the air to channel, or funnel, through the sand, instead of applying pressure uniformly thereto, and one principal object of the present invention is to provide means for overcoming this tendency. Another object is to provide means for imparting a rotary action to the air as it is admitted to the air chamber over the same, thus further preventing funneling. Still another object is to prevent sand from being blown back through the exhaust valve and so cutting the same. To the accomplishment of the foregoing and related ends, said invention, then, consists of the means hereinafter fully described and particularly pointed out in the claims, the annexed drawing and the following description setting forth in detail certain mechanism embodying the invention, such disclosed means constituting, however, but one of various mechanical forms in which the principle of the invention may be used.

In said annexed drawing:

Fig. 1 is a vertical sectional view of a mold or core filling machine in which the present improvements have been incorporated; Fig. 2 is a vertical sectional detail view of one part of the mechanism, showing modification in construction; Fig. 2^a is a transverse section taken in the plane indicated by the line *a*—*a*, Fig. 2; and Figs. 3 and 4 are vertical sectional views similar to Fig. 2, but showing the other modified forms of construction.

The general construction of the core filling machine illustrated is more or less typical, consisting of a base 1, on which is mounted a vertically reciprocable table 2 adapted to support one or more core boxes 3. Associated with such table is a fixed abutment 4 and a movable abutment 5, by means of which such boxes may be clamped to the table. Movable supported above the table so as to be shift-

able into and out of alignment with the core boxes 3, when supported on the latter, is a sand chamber 6. The latter is shown in such aligned position in Fig. 1, but in another position, i. e., when moved to the right from that shown in said figure, the sand chamber is aligned with a hopper 7, through which sand may be supplied to said chamber.

Located above the path of travel of said sand chamber in fixed alignment with the position occupied by the latter when aligned by the core box or boxes is an air chamber 8. Such air chamber is provided with a gasket 9 adapted to make a close fitting contact with the upper end of the sand chamber when in aligned position and said air chamber is also provided in its upper portion with a port 10 for admitting air under pressure, such air being supplied through a conduit 11 under control of a valve 12. Another valve 13 controls a port 14 whereby the air in chamber 8 may be exhausted when desired.

In the normal operation of the machine, the sand chamber 6 after receiving through hopper 7 a proper quantity of sand is shifted into the position shown in Fig. 1, the core box or boxes 3 are clamped to the table 2 and the latter elevated to press against a perforated plate 15 that forms the bottom of said sand chamber. At the same time the upper end of the latter is pressed against the gasket 9 to form a sealed connection with air chamber 8. Valve 13 being closed, valve 12 is opened to admit air under pressure into chamber 8 and the sand in chamber 6 is thereby forced through the openings in plate 15 into the cavities in the core boxes.

In order to prevent the tendency which such air otherwise has of channeling through the body of sand in chamber 6, I provide a baffle 16 directly below port 10 in air chamber 8, such baffle being suitably supported as by rods 17 and preferably being in the form of a concave disk with concave side directed toward such port. As a result, the air which enters through the port with considerable force strikes the baffle and is thereby diverted outwardly and around such baffle, filling the air chamber as well as the sand chamber above the body of sand in the latter uniformly, with

the result that the sand is compacted and forced downwardly as a mass. In other words, the tendency of the air to find a channel and flow in a stream through the body of sand is greatly minimized, if not entirely eliminated. The interposition of such baffle further serves to prevent sand from being carried out with the air through port 14, when exhaust valve 13 is opened, thus reducing the serious cutting action to which said valve is otherwise subjected.

In order to impart a rotary or swirling motion to the air as it enters chamber 8, the walls of the latter may be provided with spiral, inwardly projecting ribs 8a, as clearly shown in Fig. 1. The effect of such rotary action of the air is still further to reduce its tendency to channel or funnel through the sand.

In Fig. 2 there is shown a modified form 20 of baffle 18 which differs from the baffle 16 in that it is provided with a peripheral downwardly inclining flange 19. The function of this flange is to assist further in deflecting downwardly any particles of sand that may 25 be thrown upwardly by the force of the air entering the sand chamber 6 and striking the body of sand therein, as well as to prevent sand being carried out through exhaust port 14 when exhaust valve 13 is opened, as previously described. In order to assist in giving 30 the air desired swirling or rotary motion, this flange 19 is preferably formed with spiral corrugations 19a, as illustrated in Fig. 2a. It will be understood that such corrugated 35 flange may be employed either alone, as shown in said Fig. 2a, or in conjunction with spiral ribs 8a for the purpose last stated.

The baffle may also take on other forms. Thus, in Fig. 3 there is shown a simple, flat 40 disc-like plate 20 and in this connection further modification is also shown in that the inner wall of air chamber 8 is shown as of tapering or conical form, such wall diverging outwardly from the upper end where the air enters to the lower end designed to contact 45 with the upper end of sand chamber 6.

In Fig. 4 there is shown a concave disc, similar to disc 16, but with the concave side thereof directed downwardly, i. e., away from 50 the port. Also in this figure a further modification in the inner wall of air chamber 8 is shown in that such wall converges inwardly toward its lower end which is designed to contact with the upper end of sand chamber 55 6.

It will be understood that the various modified forms of construction illustrated in the several figures thus described may be variously combined, all within the spirit of the 60 invention. Thus the wall of chamber 8 as shown in Fig. 1 with or without the spiral ribs 8a may be of tapering form, converging either upwardly or downwardly as illustrated in Figs. 3 and 4 respectively.

Other modes of applying the principle of

my invention may be employed instead of the one explained, change being made as regards the mechanism herein disclosed, provided the means stated by any of the following claims or the equivalent of such stated means be 70 employed.

I therefore particularly point out and distinctly claim as my invention:

1. In mold and core filling mechanism, the combination of an open-ended sand-chamber, an air-chamber adapted to have tight-fitting engagement with the open end of said sand-chamber and provided with a port for admitting air under pressure, an imperforate baffle located in the path of air entering through such port, the edges of said baffle being spaced from the sides of said air chamber.

2. In mold and core filling mechanism having an open-end sand-chamber, an air-chamber adapted to have tight-fitting engagement with the open end of said sand-chamber and provided with a port for admitting air under pressure, a baffle located in said air chamber in the path of air entering through such port, said baffle being in the form of a concave disc with concave imperforate side directed towards such port, and having its edge spaced from the walls of said air-chamber.

3. In mold and core filling mechanism, having an open-ended sand-chamber, an air-chamber adapted to have tight-fitting engagement with the open end of said sand-chamber and provided with a port for admitting air under pressure, a baffle located in the path of air entering through such port, said baffle being in the form of an imperforate concave disk with concave side directed towards such port and further having a reversely inclining flange, the edge of said flange and the wall of said air-chamber defining an annular passage to said sand chamber out of the line from said port to said chamber.

4. In mold and core filling mechanism having a sand-chamber, an air-chamber adapted to have tight-fitting engagement with the upper end of said sand-chamber and provided with a port for admitting air under pressure, said sand and air-chambers being relatively movable transversely of each other, means for supplying sand to said sand-chamber when out of alignment with said air-chamber, means for supporting a core box in sand receiving position below said sand-chamber, means for reversing the flow of air in its course from said air port to said sand-chamber.

5. In mold and core filling mechanism having a sand-chamber, an air-chamber adapted to have tight-fitting engagement with the upper end of said sand-chamber and provided with a port for admitting air under pressure, said sand and air-chambers being relatively movable transversely of each other, means for supplying sand to said sand-chamber when

out of alignment with said air-chamber, means for supporting a core box in sand receiving position below said sand-chamber, means in said air-chamber located below such 5 port, for directing air from said air port to said sand chamber in a tortuous course.

6. In mold and core filling mechanism of the type having a sand-chamber, an air-chamber adapted to have tight-fitting engagement with the upper end of said sand-chamber and provided with a port for admitting air under pressure, said sand and air-chambers being relatively movable transversely of each other, means for supplying sand to said sand-chamber when out of alignment with said air-chamber, means for supporting a core box in sand receiving position below said sand-chamber, a baffle in said 10 air-chamber located below such port, said baffle being in the form of an imperforate member masking said port but spaced axially therefrom and spaced at its edge inwardly from the wall of said air-chamber.

20 7. In mold and core filling mechanism, the combination of an open-ended sand-chamber, an air-chamber adapted to have tight-fitting engagement with the open end of said sand-chamber and provided with a port for admitting air under pressure, and means adapted to 25 impart a swirling action to air entering through such port.

8. In mold and core filling mechanism, the combination of an open-ended sand-chamber, an air-chamber adapted to have tight-fitting engagement with the open end of said sand-chamber and provided with a port for admitting air under pressure, and spiral ribs in 30 the side-wall of said air chamber adapted to impart a swirling action to air entering through said port.

40 9. In mold and core filling mechanism of the type including an open-ended sand-chamber, an air-chamber adapted to have tight-fitting engagement with the open end of said sand-chamber and provided with a port for admitting air under pressure, a baffle located in the path of air entering through such port, said baffle being in the form of a concave disk with concave side directed towards such port and further having a reversely inclining flange formed with corrugations adapted to 45 impart a swirling action to air entering through such port.

50 10. In mold and core filling mechanism, the combination of an open-ended sand-chamber, an air-chamber adapted to have tight-fitting engagement with the open end of said sand-chamber and provided with a port for admitting air under pressure, and a baffle located 55 in the path of air entering through such port, said baffle being in the form of a concave disk with concave side directed towards such port and further having a reversely inclining flange formed with corrugations 60 adapted to impart a swirling action to air 65

entering through such port, and spiral ribs on the side-wall of said chamber adapted to assist in imparting such swirling suction to the air.

11. In mold and core filling mechanism 70 having a sand-chamber, an air-chamber adapted to have tight-fitting engagement with the upper end of said sand-chamber and provided with a port for admitting air under pressure, said sand and air-chambers being 75 relatively movable transversely of each other, means for supplying sand to said sand-chamber when out of alignment with said air-chamber, means for supporting a core box in said receiving position below said sand-chamber, means for admitting air around the edge 80 of the upper end of the sand-chamber out of direct line from said air port.

12. In mold and core filling mechanism 85 having a sand-chamber, an air-chamber adapted to have tight-fitting engagement with the upper end of said sand-chamber and provided with a port for admitting air under pressure, said sand and air-chambers being 90 relatively movable transversely of each other, means for supplying sand to said sand-chamber when out of alignment with said air-chamber, means for supporting a core box in sand receiving position below said sand-chamber, means for admitting air around the 95 edge of the upper end of the sand-chamber out of direct line from said air port, and means for agitating the air in the sand-chamber.

Signed by me, this 20th day of July, 1931. 100
MERTON W. ZEMAN.
